DOOR LOCK

John W. Lakin, Detroit, Mich., assignor to
Ternstedt Manufacturing Company, Detroit,
Mich., a corporation of Michigan

Application July 22, 1938, Serial No. 220,631

2 Claims. (Cl. 292—279)

This invention relates to a door lock particularly adapted for an automobile door.

This invention contemplates a door lock of simple structure which obviates the need for an outside door handle which projects beyond the face of the outside door panel and which, when the bolt is released, will assist in throwing the door open.

The invention relates to a door lock with a rotary gear bolt and in particular to the pawl and push button control for the rotary gear bolt.

In the drawings:

Fig. 1 is an outside fragmentary elevation of an automobile door with the instant lock assembled thereto.

Fig. 2 is a horizontal section through the door and lock assembly.

Fig. 3 is a vertical section through the rotary gear door bolt showing the body jamb pillar and bolt keeper in elevation.

Fig. 4 is a front elevation of the keeper.

Fig. 5 is a front elevation of the lock disassembled from the door.

Fig. 6 is a vertical section through the door showing the lock in elevation as viewed from the right-hand side of Fig. 5. The bolt is undogged.

Fig. 7 is a fragmentary horizontal section through the door and body jamb pillar.

Fig. 8 is a view similar to that shown in Fig. 6 showing the lock when the rotary gear bolt is interengaged with the keeper.

Fig. 9 is a view similar to Fig. 8 but showing the position of the parts just after the bolt has been undogged and disengaged from the keeper.

Figs. 10 and 11 are details of the sliding pawl and toggle arrangement for dogging the bolt.

Fig. 12 is a detail of the push button control on the inside of the door.

In the drawings there is shown a vehicle door and a body jamb pillar 2. The outside door panel is referenced 3 and the inside panel 4.

The jamb pillar 2 is provided with a combination dovetail socket and keeper. This keeper comprises a toothed rack 5 carried on a screw 6 which can be turned to adjust the rack inwardly and outwardly of the body along the face of the jamb 2. A shoe 7 having an inclined face 8 is mounted opposite and above the rack member 5 for sliding movement along the face of the jamb pillar inwardly and outwardly of the body. The shoe 7 and rack 5 are mounted within the keeper housing 9 and secured to the jamb pillar by bolts 10.

The lock comprises an angle frame 12. A bolt 13 in the form of a gear segment is fixed on shaft

14 on the outside of the door lock pillar 15. The shaft 14 passes through and is journaled in the portion 16 of the latch frame 12 which extends along the inside face of the door lock pillar 15. A ratchet 17 is fixed on the shaft 14 within the door and on the opposite side of the latch frame from the bolt 13. Since both the ratchet 17 and bolt 13 are fixed on the shaft 14, rotation of the bolt 13 correspondingly rotates ratchet 17.

A torsion spring 18 has one end 19 secured to the inner end of the shaft 14 and the other end 20 secured to a lug 21 struck out of the latch frame.

The gear bolt 13 is provided with a plurality of teeth 22 and a lug 23. The torsion spring 18 normally tends to rotate the ratchet 17 and the bolt 13 counterclockwise as viewed in Figs. 3 and 6. A stop lug 24 is struck out of the latch frame and engages ratchet tooth 25 to arrest counterclockwise rotation of the ratchet 17 and bolt 13. In the closing of the door the rotary gear bolt 13 meshes with the rack keeper 5 which rotates the gear bolt 13 and ratchet 17 clockwise (Figs. 3 and 6) and causes the torsion spring 18 to wind up.

When the rotary gear bolt is interengaged with the keeper 5, counterclockwise rotation (Fig. 3) of the rotary gear bolt is prevented by pawl 26 interengaging one of the teeth 25 of the ratchet 17. The pawl 26 is pivoted by pin 27 to toggle lever 28. Toggle lever 28 is pivoted by pin 29 to toggle lever 30. Toggle lever 30 is pivoted on pin 31 which is fixed to the latch frame and toggle cover plate 32. Loop spring 33 is mounted between flange 34 of cover plate 32, pawl 26 and toggle lever 28 and normally holds the pawl 26 against flange 35 of cover plate 32. Pin 27 is slidably guided in slot 36 in cover plate 32 and slot 37 in part 16 of the lock frame 12.

A torsion spring 38 is mounted over pin 31 and has one end 39 engaged over flange 40 of cover plate 32 and the other end 41 presses against arm 42 of toggle lever 30. Thus torsion spring 38 normally tends to rotate toggle lever 30 counterclockwise, as viewed in Fig. 9, and to hold the toggle lever straightened, as shown in Figs. 6 and 10, that is, with pin 29 slightly to the left of a center line passing through pins 27 and 31.

When the door is open, rotary gear 13 assumes the position shown in the dotted lines, Fig. 3, and the ratchet 17 is in the position shown in Fig. 6 with tooth 25 against stop 24. In the closing of the door eccentric lug 23 first engages the rack keeper 5 causing the gear bolt 13 to rotate clockwise, Fig. 3, as the teeth of the gear bolt

mesh with the teeth of the rack keeper 5. This causes clockwise rotation of the ratchet 17 from the position shown in Fig. 6 to that shown in Fig. 8. As the ratchet rotates clockwise, torsion spring 18 is loaded and spring 33 causes pawl 26 to ride over and interengage the first of the ratchet teeth 25 and then ride over and interengage the second ratchet tooth 25, as shown in Fig. 8. At this time the door is closed and latched 10 with the rotary gear bolt 13 interengaged with the keeper 5, as shown in Fig. 3. In the closing of the door the circular face 45 of the bolt 13 engages the inclined face 8 of the shoe 7 causing the shoe 7 to yield and slide inwardly or to the 15 right, Fig. 3, with the bolt and at the same time hold the bolt in mesh with the rack keeper 5. Since, as shown in Fig. 8, the toggle 28, 30 is straightened, the pawl 26 positively prevents counterclockwise rotation of the gear bolt and 20 prevents disengagement of the bolt and rack keeper.

Disengagement of the bolt is effected by breaking the toggle at the knee, that is, by moving pin 29 slightly to the right of center, as viewed in Fig. 11. This is accomplished from the outside 25 of the door by a spring projected push button 46 having a lug 47 which, when the push button 46 is pushed inwardly, Fig. 11, engages the toggle at the knee and throws pin 29 to the right of center 30 to trip the toggle whereupon the toggle and pawl permit counterclockwise rotation of the ratchet 17 by the loaded torsion spring 18. This causes the bolt 13 to roll out of engagement with the keeper 5 and throw the door 1 open. As soon as 35 the pawl 26 clears teeth 25, torsion spring 38 straightens the toggle and throws it to the position shown in Fig. 6 where, upon closing the door, the pawl 26 is again in position to interengage the teeth 25 of the ratchet to prevent counterclockwise rotation of the same.

Push button 46 comprises a plunger which can be rotated through 90° which places the lug 47 in the position shown in Fig. 6. In this position, even though the push button 46 is pressed inwardly, the lug 47 will not engage the toggle to release the pawl and thus the push button is ineffective to release the pawl. The push button is provided with a conventional key controlled cylinder lock for locking the plunger in either operative or inoperative position. The cylinder lock is made so that the tumblers in the key plug will prevent rotation of the plug only after the key plug has been turned to locked position and the key then removed. If the key plug is not turned 55 to locked position, then the plug can be freely rotated even though the key is not inserted in the plug. In view of the fact that the key controlled cylinder lock is not covered by the claims or included as an element in the claims, it is believed 60 that further explanation is not necessary.

When the door is latched, the pawl 26 can be released from within the car by means of push button 48 which is carried by the inside door handle 50. The inside door handle 50 serves only as a pull-to and therefore is fixed to the inside door panel 4. Push button 48, when depressed, acts through lever 51, draft link 52 and bell crank lever 53 which engages arm 42 of toggle lever 30 to swing the toggle lever 30 clockwise, Fig. 8, to 70 break the toggle. This renders dog 26 ineffective to prevent counterclockwise rotation of the ratchet and bolt whereupon torsion spring 18, acting through the rotary gear bolt, throws the door open, as above described.

75 Lever 51 is supported on plate 54 by pin 55.

Torsion spring 56 has one end secured to the plate 54 as at 57 and the other end secured to the lever 51 as at 58. Torsion spring 56 tends at all times to rotate lever 51 clockwise, Fig. 12, and maintain push button 48 projected. Bell crank 53 is pivotally mounted on the latch frame by pin 60.

The latch can be locked from within the body by a push button and rod 61 which is connected to a sliding plate 62. Plate 62 is slidably supported on the lock frame by pins 63 and 64. Pin 64 is fixed to lug 67 and turned outwardly 90° from part 16 of the latch frame. A coil spring 65 and washer 66 are mounted between the head of the pin 64 and plate 62. Plate 62 is provided with a hump 62' which engages either the upper or lower edge of lug 67. The coil spring 65 is at all times held under compression and thus frictionally holds the plate 62 against lug 67 and cooperates with lug 67 and hump 62' to retain 20 plate 62 in either raised or lowered position. The sliding plate 62 is connected at its lower end in enlarged slot 69 to the rotatable push button cylinder by pin 68.

When the door is closed, the outside push button 25 can be rendered ineffective to unlatch the door by pushing downwardly on button 61 which slides plate 62 downwardly from the position shown in Fig. 8 to that shown in Fig. 6. As the plate 62 slides downwardly it acts through pin 68 30 to rotate the push button cylinder 90° and thus swing lug 47 so that it clears the toggle lever. If the push button is depressed when lug 47 is in the position shown in Fig. 6, the lug will not engage the toggle lever and thus the push button is ineffective to break the toggle and release the bolt 13.

Of course, both when the door is open and when it is closed, a key can be inserted in the lock cylinder, and push button 46 turned to place 40 the lug 47 either in the position shown in Fig. 6, in which case the door will be locked, or in the position shown in Fig. 8 where the door is unlocked, that is, the push button 46 can be depressed to release pawl 26 from the ratchet. 45

If, while the door is open, push button 61 is depressed to swing lug 47 to inoperative position, Fig. 6, then upon closing the door, as the bolt 13 rolls along the keeper 5, the ratchet 17 is correspondingly rotated which causes the cam lug 70 50 to engage flange 71 on plate 62 and raise the same from the position shown in Fig. 6 to that shown in Fig. 8. This automatically returns lug 47 to operative position where the push button 46 can be depressed to retract dog 26 and release 55 the bolt 13.

The door is provided with an outside handle 72 which is fixed to the door and is non-rotatable.

I claim:

1. A door lock comprising a frame, a rotary bolt rotatable in one direction in the closing of the door and in a counter-direction in the opening of the door, a ratchet fixed to said bolt for rotation therewith, a pawl interengageable with said ratchet for dogging said ratchet against counter-rotation, a toggle lever, a fixed pivotal connection between one end of the toggle lever and the latch frame, a slidable connection between the other end of the toggle lever and the frame, a pivotal connection between the pawl and the slidable end of the toggle lever, resilient means tending to maintain the toggle in made position wherein the toggle is effective to dog the ratchet and bolt against rotation in door opening direction, and a rotatable push button in- 75

cluding a portion for contacting the toggle to break the same when the push button is depressed, the said push button being rotatable to another position to swing the said portion out of contact with the toggle whereby the push button is ineffective to break the toggle.

5. 2. In combination with a door, a door lock of the type having a toothed keeper, a rotatable gear bolt adapted to mesh with the keeper and be rotated in one direction in the closing and in 10 a counter-direction in the opening of the door, a ratchet fixed to said bolt for rotation therewith, a pawl for dogging said ratchet against counter-

rotation, a push button operable from the outside of the door to release the pawl from said ratchet, means including a slidale member which can be set on the inside of the door to render the push button ineffective to release the 5 pawl, and a cam on the said ratchet engageable with the slidale member during the closing of the door to release the said slidale member whenever the same is set while the door is open and render the push button effective to release 10 the pawl.

JOHN W. LAKIN.
